UNITED STATES PATENT OFFICE.

FRANK C. HEINEN, OF CHICAGO, ILLINOIS.

SNOW-PLOW.

1,144,763.

Specification of Letters Patent. Patented June 29, 1915.

Application filed December 8, 1911. Serial No. 664,634.

To all whom it may concern:

Be it known that I, FRANK C. HEINEN, a resident of Chicago, in the county of Cook and State of Illinois, have invented certain new and useful Improvements in a Snow-Plow, of which the following is a full, clear, and exact description.

The invention relates to snow-plows and designs more particularly to provide an improved plow or plowing attachment which may be mounted upon a motor-vehicle to remove the snow from an uneven street.

One object of the invention is to provide an improved plow which is particularly adapted to be operated over a pavement or road and in which provision is made for causing the plow to ride over obstructions and to adapt itself to uneven road-surfaces.

Another object of the invention is to provide an improved plow which may be attached to a motor-truck of usual construction so that the plow may be employed as an attachment to the truck and so that the truck may be used to operate the plow to remove snow from the road.

Lastly the invention designs to provide a snow-plow of improved construction.

The invention consists in the novel features hereinafter set forth and more particularly defined by claims at the conclusion hereof.

In the drawings: Figure 1 is a side elevation of a motor driven truck embodying the invention. Fig. 2 is a side elevation of a portion of the plow, showing in dotted lines, different positions which one of the plowshares may be caused to assume. Fig. 3 is a horizontal section through the plowshare, the spring-connections for the adjustable share being shown in elevation. Fig. 4 is a vertical section on line 4-4 of Fig. 1. Fig. 5 is a section on an enlarged scale taken on line 5-5 of Fig. 4. Fig. 6 is a detail section showing the device for securing the rear ends of the side-rails of the plow-supporting frame to the side-rails of the truck-frame. Fig. 7 is a detail perspective showing the manner in which the plow frame is secured to the front of the motor truck frame.

The improved snow-plowing mechanism is adapted to be attached to a motor-vehicle of usual construction and comprising carry-

ing wheels *a*, traction-wheels *b*, a frame *c*, a seat *d* and a radiator *e*, as well understood in the art.

The plowing attachment comprises a fixed share 12 which is inclined relatively to the lines of travel, and has its lower edge disposed a sufficient distance above the ground, so that it will clear any obstructions on the road. The upper and lower edges of share 12 are curved and the inclination of the share is such as to deflect the snow in its path, to one side of the vehicle. A supplemental and movable share 13 is adjustably sustained so that it will adapt itself to uneven portions of a roadway, is also inclined to the line of travel of the vehicle and has its lower edge disposed to work below share 12, and in close contact with the ground, so that this share will follow the fixed share and throw the snow nearest to the ground or that over which share 12 passes, to one side of the vehicle. Both shares 12 and 13 are sustained by a supporting-frame which is adapted to be attached to and removed from the vehicle-frame *c* and comprises side-bars 14 which have their front ends bent downwardly and rigidly secured to brackets 15 on the back of share 12. The rear ends of side-bars 14 of this detachable frame are secured in blocks 16 respectively, which are adapted to rest against the sides of the frame *c*. Each block 16 has secured thereto, by the bolts 17, a clip 18 which is adapted to fit against the under side of one of the side rails of frame *c*, and has a groove 19 which is adapted to receive the base flange on said rail. A lug 20 secured to block 16 by bolts 21, is extended laterally to overlie and fit against the top of said rail and has a groove 22 in which the top-flange of said rail will fit. Bolts 20 and a hook-plate adapted to engage the front rail of the truck-frame, serve to detachably secure the central portion of cross-bar 23 to the truck-frame. These attaching-devices serve to rigidly secure the rear end of rails 14 of the plow-supporting frame to the side-rails of the truck-frame *c*, without the necessity of weakening or drilling said rails. By removing the clips 18 and lugs 20 the rear ends of side-bars 14 may be disconnected from the truck. The plow-supporting frame also comprises a cross-bar 23 which is adapted to

extend over the front end of the truck-frame in front of the radiator *e*, and has downwardly extending members or uprights 24 integrally formed therewith. These uprights are rigidly secured to side-bars 14 by plates 25 and 26. The front end of the plow-supporting frame is secured to the front end of the truck-frame, by blocks 27 which fit in corners between the uprights 24 and cross-bar 23 and are adapted to fit against the outer sides of the truck frame, and plates 28 which are bolted to said blocks are adapted to engage the underside of the truck frame. By disconnecting the rear ends 10 of side-bars 14 from the truck frame and releasing or removing plates 28 the plow supporting frame may be detached from the truck-frame.

Braces 29 extend between, and are secured 20 to, the lower portion of uprights 24 and side-bars 14 and secure the lower ends of the uprights against backward stresses.

The adjustable plow-share 13 is pivotally sustained by a rod 30 which extends through 25 lugs 31 secured to the back of said share and forwardly extending arms 32 on uprights 33, which are slidably mounted in ways formed between uprights 24, and plates 26 and 25 and side-bars 14. Plates 34 are secured to uprights 24 and serve to confine the lower portion of uprights 33 against outward movement and the front ends of braces 29 are extended along the inner faces of these uprights respectively, so that uprights 33 will be vertically slidable therebetween. At each side, plow share 13 is yieldingly held in operative position by a device for pressing it into such position, and which permits the lower portion of said share to 40 swing or tilt backwardly when an insurmountable obstruction is met with. Each of these devices consists of a rod 36 which has its front end pivoted in lugs 37 secured to the back of share 13 near the lower edge thereof, a spring 38 coiled around said rod and engaging a nut 39 which is screw-threaded thereon, a bracket 40 secured to the lower end of upright 25 and through which rod 36 is loosely extended, and nuts 41 which are screw-threaded to the rear ends 50 of the rod and serve as adjustable stops for limiting the action upon the share by the spring. By adjusting nuts 39, the tension of the springs may be varied. Consequently, when an obstruction is encountered, the plow-share will be tilted backwardly by the obstruction as indicated by the dotted lines in Fig. 2. Each side of the share 13 is vertically movable independently of the other, so that in driving over an uneven roadway or when share 13 has been tilted backwardly against the force of springs 38 and the obstruction tends to raise the share, either or 60 both sides of the share may be raised by the obstruction. For this purpose a spring-

pressed device is applied to each upright 33. Each of these devices consists of a rod 42 secured to the inturned end of the upright and extending through one end of a lever 43, nuts 44 on the upper end of said rod, 70 a coiled spring 45 between the lever and the upper end of upright 33 and another coiled spring 46 between the lever and the nuts 44. Lever 43 is centrally pivoted as at 47 to a collar 48 which is screw-threaded to a vertical rod 49 having a hand-wheel at its upper end whereby the rod may be turned to raise and lower the collar. The lower end of this rod is swiveled in a suitable bearing 51 which is formed of sections and permits the head 80 52 on the lower end of the rod to be rotated, but holds the rod against vertical movement. This construction permits either of the uprights 33 to slide upwardly in response to unevenness of, or obstruction on, the road. 85 The pressure of the share 13 on the road may be regulated by adjustment of collar 48 which will, through the spring-connections with the uprights respectively, raise and lower them to correspondingly adjust share 90 13. When one side of the share 13 is raised by a small obstruction on the rod, the upright 33 on that side will raise against the force of spring 45 applied thereto and tilt or tend to tilt lever 43 against the spring 45 95 at the opposite side, which will permit the lever to tilt. As soon as the plow has traveled over any unevenness the share 13 will be caused to assume its former relation in contact with the ground. When an obstruction is encountered, which would otherwise arrest the machine, share 13 will swing backwardly against the force of springs 38 and the share will be curved rearwardly and downwardly to such an extent that it will be deflected upwardly by the obstruction against the force of springs 45. In this manner obstructions will not wreck the plowing-mechanism and the share 13 may be used to closely scrape the ground without 100 danger of breakage and without requiring frequent manipulation upon the part of the operator. It will be understood that the pivotal points of the pivotal connection are sufficiently loose to permit them to operate as described. In practice, the plow 13 may be caused to act as a scraper and its pressure upon the road may be varied according to the condition of the snow by adjustment 105 of screw 49.

The invention thus provides an improved snow-plowing mechanism which may be readily applied to a motor-vehicle of usual construction. It also provides a share which may be operated to scrape the ground and which will yield responsively to obstructions and inequalities of the ground, without danger of breaks.

The invention is not to be understood as restricted to the details set forth, as these 110 115 120 125 130

may be modified within the scope of the appended claims without departing from the spirit and scope of the invention.

Having thus described the invention, what I claim as new and desire to secure by Letters Patent, is:

1. In a snow-plow, the combination of a truck frame having sides, a carrying structure having side bars adapted to extend on the outer side of the sides of the truck frame and comprising a cross bar extending between said side bars and adapted to extend across one end of the truck frame, a plow rigidly secured to said structure, another plow in the rear of the rigidly supported plow adjustably connected to said structure, and means for securing the side bars of the carrying structure to the sides of the truck frame.
  2. In a snow-plow, the combination of a truck frame, a plow carrying structure having downwardly extending rigid members at its sides, a plow rigidly connected to said structure, forwardly extending supporting arms adjustably mounted on said structure, a plow pivoted to the front of said arms, and yielding spring connections pivoted to the pivoted plow and connected to the lower ends of said members.
  3. In a snow-plow, the combination of a truck frame, a plow carrying structure having downwardly extending, rigid members at its sides, a plow rigidly connected to said structure, forwardly extending supporting arms adjustably mounted on said structure, a plow pivoted to the front of said arms and yielding spring connections pivoted to the pivoted plow, below the point where it is pivoted to said arms, and connected to the lower ends of said members.
  4. In a snow-plow, the combination of a truck frame, a plow carrying structure having downwardly extending rigid members at
- its sides, a plow rigidly connected to said structure, forwardly extending supporting arms adjustably mounted on said structure, a plow pivoted to the front of said arms, rods pivotally connected to the pivoted plow and slidably connected to the lower ends of said members, and springs on said rods.
5. The combination with a truck frame, of a plow frame comprising members adapted to be secured to the sides of the truck frame, a cross-member adapted to extend across the front of the truck frame and be secured thereto, supporting arms slidably mounted in said frame, a stationary plowshare sustained by said frame, and disposed in front of the truck frame and angularly thereto, a movable plowshare disposed behind the stationary plowshare and to operate at a lower level, said rear share being pivotally secured to said supporting arms and means for adjustably and yieldingly securing said arms.
6. The combination with a truck frame, of a plow frame comprising members adapted to be secured to the sides of the truck-frame, and a cross member adapted to extend across the front of said truck frame and to be secured thereto, of a stationary plowshare sustained by said frame and disposed in front and angularly thereof, an adjustable plowshare disposed behind the stationary share and to operate at a lower level, said rear share being pivotally sustained to swing about a point between the top and bottom edges thereof, spring-means for yieldingly holding the rear share against movement in a horizontal plane and spring means for yieldingly holding the rear share against movement in a vertical plane.
